FLUID COMPRESSOR

Albert E. Roy, Los Angeles, Calif.

Application September 19, 1941, Serial No. 411,542

8 Claims. (Cl. 60—54.6)

My invention relates to a compressor for fluids and which is particularly adapted for use in conjunction with hydraulic mechanism and especially to that adapted for association with hydraulic brake mechanisms and more specifically relates to the fluid pressure producing devices for such mechanisms.

Another object of my invention is to provide a novel mechanism comprising a low pressure cylinder and a high pressure cylinder which are in communication with one another during the initial operation of the compressor device, and including novel valve means to cut off communication between the high and low pressure cylinders when the fluid compression member has moved forward on its compression stroke and to prevent the pressure in the low pressure cylinder from rising above a desired value.

A further object of my invention is to provide novel mechanism comprising low and high pressure cylinders in communication with each other during initial movement of a common fluid compression element having piston heads mounted thereon, and reciprocal in each of said cylinders, and including novel means for adjusting the maximum value of the pressure built up in the low pressure cylinder during the brake applying movement of the parts, and to return liquid expelled from said low pressure cylinder into a reservoir after communication with the high pressure cylinder has been cut off from said low pressure cylinder when the parts move to released position.

A still further object of my invention is to provide a novel pressure cylinder construction comprising high and low pressure cylinders and novel valve and port means whereby on the commencement of the operative movement of fluid compression pistons in said cylinders, the pressure in the low pressure cylinder during the initial movement of the pistons is quickly transferred to the high pressure cylinder for taking up the slack in the brake mechanism parts, and then pressure is transmitted at a higher value in the high pressure cylinder by further operative movement of the pistons, and whereby any subsequent pressure in the low pressure cylinders is relieved during further operation of the fluid compression member.

A still further object is to provide a novel fluid compressor whereby the fluid pressure is controlled by novel valve and by-pass means to obtain proper balance of the fluid pressure during the compression stroke.

A still further object is to provide a novel fluid

compressor whereby a remote mechanism may be instantly operated and high pressures immediately conveyed thereto for subsequent operating purposes.

5 A still further object is to provide a novel, simple and efficient fluid compressor adapted to be connected to pressure distributing lines of hydraulic braking mechanism and whereby a high line pressure may be maintained in such fluid distributing lines.

The invention also resides in the parts and combinations of parts, and in the particular provision, relative disposition and cooperative functions of the parts as hereinafter more fully described in detail, illustrated in the drawings, and particularly pointed out in the claims.

Other objects, advantages and features of invention may appear from the accompanying drawings, the subjoined detail description, and

20 the appended claims.

The accompanying drawings illustrate the invention in some of the forms I at present deem preferable, but it is to be understood that the scope of the invention is not limited to the illustrative embodiments shown and described, as the principles involved are susceptible of numerous other applications that will readily occur to persons skilled in the art.

Figure 1 is a vertical sectional view of my preferred form of pressure producing construction, and showing the piston in retracted position.

Fig. 2 is a transverse cross sectional view on reduced scale, and taken on line 2—2, Fig. 1, and looking in the direction of the arrows.

35 Fig. 3 is an enlarged detail plan view of the face of the relief valve, taken on line 3—3, Fig. 1, and looking in the direction of the arrows.

Fig. 4 is a vertical sectional view analogous to Fig. 1 showing a modified embodiment of my

40 invention.

Fig. 5 is a fragmental axial sectional view showing a modified form of the high pressure cylinder piston head and associated valve structure.

In the preferred form of the invention illustrated in Figs. 1-3 of the drawings, it will be seen that I provide a low pressure cylinder A and a high pressure cylinder B of smaller diameter than cylinder A, and arranged co-axially therewith, and pressure release means generally indicated at C for the low pressure cylinder A, said pressure release means being arranged in a fluid reservoir and also serves to provide communication between the reservoir and cylinder A.

A brake or operating pedal 4 is pivoted at 2 50 to arms 2' that extend from a housing A, and has

a lower arm 3 pivotally connected by pivot bolt 4 to one end of a push rod 5, which is rounded at its inner end and engages the recess 5' formed in the back of the reciprocal piston element 6 to force the same inwardly into the cylinders A and B upon depression of the brake pedal 1.

An oil or fluid reservoir 7 is provided with an air bleed vent 9 that serves to keep the reservoir in communication with the atmosphere, and is formed by a plurality of ports or openings formed in a plug 10 which is removably mounted in a filling opening 10' formed in a cover plate 26 to enable fluid to be placed in the reservoir 7. To prevent fluid from splashing out through openings 9, a baffle in the form of a wad of steel wool 8 is positioned in the reservoir beneath the plug 10.

The piston element 6 is provided with a low pressure piston head 6a and a high pressure piston head 6b; a leak proof washer or rubber piston cup 11 is secured to piston head 6a by forcing the same over a head 12 and into a recess 12' formed in the piston head 6a so as to retain the same thereon and said cup 11 operates in the low pressure cylinder A to force fluid (preferably oil) therealong, and to inhibit the seepage of fluid from the cylinder past the piston. A spring 14, arranged within cylinder A and between the inner face of piston head 6a and a wall 13 that forms the inner end of the cylinder A, serves to return the piston element 6 and rod 5 to retracted or inoperative position, as shown in Fig. 1.

The piston element 6 is retained against displacement from the open end of cylinder A by a retaining ring 90 seated in a circumferential groove in the wall of the cylinder.

The high pressure piston head 6b is provided on the inner end of the reduced body portion of piston element 6 and is provided with a plurality of ports 15 that extend longitudinally through the piston head 6b and provide for controlled communication between the cylinders A and B. The piston head 6b is provided at its inner end, and within the cylinder B with a floating rubber piston cup or valve 17 which is provided with a metal ring insert 18 that overlies and forms an effective closure for the ports 15 when the piston cup or floating valve 17 is moved against the end 91 high pressure piston head 6b which forms a valve seat for the valve 17.

The valve 17 is retained in limited floating movement relative to its seat 91 by a stud bolt 19, the stem of which slidably supports a metal retaining washer 19' that preferably is frustro-conical and has four prongs 16 thereon so as to provide spaces 20 through which fluid may freely pass, as hereinafter explained. Stud 19 is screwed into a tapped bore in piston head 6b, and it will be noted that a small clearance is provided between valve 17 and the stem of stud 19, and that a bleed port or passageway 52 is drilled through the head of stud 19 and into the length of the stud stem and communicates with the clearance space 51 between the stud and valve 17. The bleed port 52 provides for communication between the interior of the high pressure cylinder B and the low pressure cylinder A through the space 51 and ports 15 when the valve 17 is moved forward against the washer 19', and valve 17 is provided with a frustro-conical recess 92 in its inner face providing a valve seat for washer 19'.

The cylinder B has a head in the form of a nut 21 threaded thereinto and is provided with a discharge port 22 that is suitably connected to a fluid pressure delivery pipe 23 which leads to the remotely located fluid actuated motors (not shown)

such as to the hydraulic cylinder in a braking mechanism.

A rubber boot or cover 24 for excluding dust and other foreign substances is secured by resilient tension to the open end of cylinder A and to a collar 93 on the push rod 5.

The removable cover plate 26 is secured by screw studs 25 against a gasket 26' to effectively close the top of reservoir 7.

10 The relief valve C as shown in Figs. 1-3, comprises a valve stem 27 carrying a valve head 28 which seats on a valve seat 29 formed in the lower end of a bushing 30 that is screw threaded at 31 into the lower wall 32 of the reservoir 7.

15 The valve stem 27 is threaded and fitted with an adjusting nut 34 for a spring 35 arranged between the head of nut 34 and the upper face 36 of an auxiliary plate valve 37, that has a tubular guide 38, slidable on the valve stem 27. The lower face of auxiliary valve 37 normally rests upon the top shoulder 39 of the body of valve head 28.

Auxiliary valve ports 40 are provided through the body of valve head 28 to permit fluid to flow therethrough from cylinder A to reservoir 7 under 25 control of auxiliary valve 37. The lower face of valve 37 is provided with a minute radial groove 56 that communicates with ports 40 either direct or through a minute circular groove 58 formed in the upper surface or on the top shoulder 39 of 30 valve head 28, and which groove 58 connects the ports 40; thereby providing a slight bleeding action between cylinder A and reservoir 7. As soon as pressure builds up in the low-pressure cylinder A, the valve 28 will close, thereafter fluid will be 35 forced upwardly through the ports 40 and against the tension of the spring 35. The tension of the spring 35 will close the auxiliary valve 37, while there is still some pressure in the cylinder A. It is this last bit of fluid under pressure which bleeds 40 through the groove 58 and thence through the radial groove 56 into the reservoir C.

Pins 42, 42' extending from bushing 30 and valve 37 are provided to limit the rotation of the floating valve 37 when the screw 34 is adjusted 45 to vary the tension of spring 35 and thus determine the degree of pressure required to operate valves 28 and 37.

The flange 94 of bushing 30 is provided on its 50 upper surface within reservoir 7 with a plurality of grooves 95 that extend radially from the grooves 96 formed in the bore of bushing 30 and through which the body of valve head 28 reciprocates, thereby providing for free flow of fluid from reservoir 7 to cylinder A when the auxiliary 55 valve 37 is closed and until the valve 28 is seated upon its seat 29 by compression of fluid in cylinder A, and upon release of such compression the valve 37 will be urged by spring 35 upon the top shoulder 39 and then the valves 37 and 28 may move 60 as a unit by gravity to open valve 28 to permit free flow of fluid from reservoir to cylinder A.

A bleed port 50 is provided to connect the cylinder B to the atmosphere through valve means C when the piston element 6 is retracted and such 65 port 50 is immediately cut off upon advancement of the piston on its compression stroke.

In the modification of the invention shown in Fig. 4 the general arrangement of co-axially arranged low and high pressure cylinders A and B and reservoir 7 with air bleed vent 9 and steel wool packing 8 for the vent are similar in construction to that shown in Fig. 1 and carry the same reference numerals as in that figure but the construction of conduits of controlling and putting the low and high pressure cylinders into com-

munication with each other and also the valve means C' serving to release excess pressure in the low pressure cylinder after communication between the cylinders has been interrupted, are of modified construction.

In Fig. 4 the low pressure cylinder A and the high pressure cylinder B are shown connected by a passage 61 formed in a wall of the housing embracing such cylinders, and is controlled by a ball check valve 62 pressed into engagement with seat 63 by a light spring 64 arranged between the ball and an adjustable abutment screw 65. It will be noted that passage 61 connects beyond the check valve 62 by a branch passage 61a with the interior of the high pressure cylinder B.

The relief valve C in Fig. 4 comprises a valve head 67 in the form of a circular disc having an upwardly projecting hollow stem 69, and a downwardly and depending skirt 70 of lesser diameter than the disc 67 and concentrically arranged relatively thereto, slidably fits in an aperture in the lower wall 32 of the reservoir 7. Slots or apertures 71 are formed in the skirt portion 70 just under the lower side of the disc 67 and when the valve 67 is seated on its seat formed by contact with wall 32 the apertures 71 will be closed.

The disc 67 is provided with apertures 72 adjacent stem 69 and within the area defined by skirt 70, and a smaller disc valve 73 is floatingly mounted by a stem 74 nested in the hollow stem 69 of disc valve 67 and underlies the apertures in position to obturate them when fluid forced from cylinder A into the reservoir 7 carries the disc valve 73 upwardly against the underside of the valve head 67. A nut 97 threaded on stem 74 retains valve 73 in position and provides for adjustment thereof relative to its seat. Pin 98 secured in stem 69 and extending through slot 99 in stem 74 prevents rotation of valve 73 where adjusting nut 97 is operated and also prevents accidental displacement of valve 73.

The relief valve head 67 normally urged against its seat by a coil spring 68 that operates between head 67 and an abutment 76 that has a threaded stem 77 extending therefrom into a threaded sleeve 78 which extends through the cover plate 26 where a knurled nut 75 is secured thereto by a set screw 79. The tension of spring 68 may be varied by rotation of the sleeve 78 thus causing up or down movement of the upper abutment 76 of the spring. A flange 100 on sleeve 78 engages the underside of cover 26 and cooperates therewith and with nut 75 to prevent axial displacement of sleeve 78 and provide for ease of assembly.

It will be noted that the cylinder head 101 for the high compression cylinder B is solid and provided with oil grooves 102, and that the rubber piston cup 103 is secured to the head 101 by the employment of a disk 104 and securing element 105.

Otherwise in the modified structure where the parts are analogous they have been given like reference characters and for the sake of brevity further description thereof is omitted.

In operation of the device shown in Figs. 1-3 and assuming the parts are initially in the released or retracted position as shown in Fig. 1, when pedal 1 is depressed the piston element 6 through rod 5 starts its compression stroke and fluid in low pressure cylinder A is displaced, at once closing valve 28 and moving piston head 17 away from piston 6b and flowing through ports 15, clearance 51 and spaces 20 into cylinder B; if washer 19 momentarily closes the clearance space 51 oil will pass through passage 52, and 75

bleed port 50 is closed by piston valve 17. This initial movement serves to immediately fill the fluid pressure delivery pipes and associated motors, due to the large compressing area of head 5 6a and cylinder A, thereby bringing the brake shoes into engagement with the brake drum with a minimum movement of the pedal 1. The pressure in cylinder B thereafter becomes high enough to move piston cup 17 against piston head 6b, 10 after which excess compressed fluid from the low pressure cylinder A raises plate valve 37 and enters reservoir 7 through ports 40. High pressure cylinder B is then sealed against escape of fluid through any path except through outlet pipe 23, and continued depression of the pedal 15 1 applies the full pressure of fluid compressed in cylinder B to the braking mechanism or the remote fluid pressure actuated motors. When pedal 1 is released spring 14 aids in returning the piston element 6 to initial position and such return becomes effective to return the pedal to retracted position and spring mechanism (not shown) of element 6 tends to create a vacuum to open valves 17 and 28 and fluid from reservoir 7 will quickly fill all parts of the cylinders 20 and connecting ports.

In the operation of the device constructed as shown in Fig. 4 the action of the parts is similar except that a bleed passage 52 is not provided, and fluid from low pressure cylinder A flows into the high pressure cylinder B during the initial operation of the device through conduit 61 past check valve 62 which is also opened during return movement of the piston element to refill the cylinder B.

In Fig. 5 as shown a modified form of valve control means for the high pressure cylinder and in which the piston element is provided with a high pressure cylinder head 120 to which a rubber piston cup 121 is secured by screw 122 threaded into axial bore 123 provided in head 120 and which screw 122 has flared head 124 that extends substantially to the periphery of the cup 121 to maintain the same in position. The screw 122 30 has an axial bore 125 that communicates with the bore 123 which is extended at its inner end by bore 126 to communicate with the low pressure cylinder. A ball check valve 127 operates to control flow of fluid between the pressure cylinder 35 so as to permit fluid to flow from the low pressure to the high pressure cylinder and to prevent reverse flow of fluid therethrough. The ball check valve 127 is normally urged into seated position by a light spring 128 operating between ball 127 and the inner end of screw 122.

From the foregoing it will be observed that in the operation of my fluid compressor a slight depression of the pedal 1 operates the piston element and such operation completely fills the fluid 40 pressure lines and fluid operated motors and places the brake shoes into engagement with the brake drums, the low pressure cylinder then cuts off and further depression of the brake pedal operates compressed fluid in the high pressure cylinder and forces the same through the fluid pressure lines for braking operation. I, therefore, obtain immediate operation of the fluid operated motors by slight pedal pressure and thereafter pedal pressure is available for braking operation, 45 whereas, heretofore considerable pedal operation was required in order to obtain high line pressure or extraneous apparatus was required.

Heretofore, the pressure in fluid distributing lines has been obtained in varying degrees from approximately nine pounds to one thousand

• pounds, and I have found from tests made with my device that the pressure in the fluid pressure distributing lines is materially increased so that fluid pressures have been obtained in varying degrees from approximately nine pounds to two thousand pounds.

I have also found that the auxiliary valve 36 may be rigidly associated with the top shoulder 39, and in that event the grooves 56 and 58 provide sufficient passage from the low pressure cylinder to the oil reservoir to relieve excess pressure that may be created therein.

I claim:

1. A fluid compressor comprising: a fluid reservoir; a low pressure cylinder supplied therefrom; a high pressure cylinder coaxial with said low pressure cylinder; a common piston element for said cylinders provided with a piston head working in the low pressure cylinder and a piston head working in the high pressure cylinder, there being a passageway in said latter head connecting said cylinders; a retaining stud extending from the forward end of said high pressure head; a floating valve loosely held on said stud for limited axial movement thereon and providing an axial annular passage around said stud communicating with said head passage when said valve is away from said head, said valve being adapted to close said head passage when seated against said head; and a washer carried on said stud forward of said valve provided with an aperture communicating with said annular passageway when said valve is seated on said head, and adapted to close the same when said valve is at the other end of its stroke away from said head; whereby fluid passes from the low pressure cylinder to the high pressure cylinder during initial operation of the piston element on its compression stroke, and is prevented from returning during completion of said stroke.

2. A fluid compressor comprising: a fluid reservoir; a low pressure cylinder supplied therefrom; a high pressure cylinder coaxial with said low pressure cylinder; a common piston element for said cylinders provided with a piston head working in the low pressure cylinder and a piston head working in the high pressure cylinder, there being a plurality of longitudinal passageways in said latter head connecting said cylinders; a retaining stud extending from the forward end of said high pressure head; a floating valve loosely held on said stud for limited axial movement thereon and providing an axial annular passage around said stud communicating with said head passages when said valve is away from said head, said valve being provided with an annular insert fast to its rear face and adapted to close said head passages when seated against said head; and a washer carried on said stud forward of said valve provided with an aperture communicating with said annular passageway when said valve is seated on said head, and adapted to close the same when said valve is at the other end of its stroke away from said head; whereby fluid passes from the low pressure cylinder to the high pressure cylinder during initial operation of the piston element on its compression stroke, and is prevented from returning during completion of said stroke.

3. A fluid compressor comprising: a fluid reservoir; a low pressure cylinder supplied therefrom; a high pressure cylinder coaxial with said low pressure cylinder; a common piston element for said cylinders provided with a piston head working in the low pressure cylinder and a pis-

ton head working in the high pressure cylinder, there being a passageway in said latter head connecting said cylinders; a retaining stud extending from the forward end of said high pressure head; a floating valve loosely held on said stud for limited axial movement thereon and providing an axial annular passage around said stud communicating with said head passage when said valve is away from said head, said valve being adapted to close said head passage when seated against said head; an axial bleed passage in said stud connecting said annular passage with the high pressure cylinder irrespective of the position of said valve on said stud; and a washer carried on said stud forward of said valve provided with an aperture communicating with said annular passageway when said valve is seated on said head, and adapted to close the same when said valve is at the other end of its stroke away from said head; whereby fluid passes from the low pressure cylinder to the high pressure cylinder during initial operation of the piston element on its compression stroke, and is prevented from returning during completion of said stroke.

4. A fluid compressor comprising: a fluid reservoir; a low pressure cylinder supplied therefrom; a high pressure cylinder coaxial with said low pressure cylinder; a common piston element for said cylinders provided with a piston head working in the low pressure cylinder and a piston head working in the high pressure cylinder, there being a plurality of longitudinal passageways in said latter head connecting said cylinders; a retaining stud extending from the forward end of said high pressure head; a floating valve loosely held on said stud for limited axial movement thereon and providing an axial annular passage around said stud communicating with said head passages when said valve is away from said head, said valve being provided with an annular insert fast to its rear face and adapted to close said head passages when seated against said head; an axial bleed passage in said stud connecting said annular passage with the high pressure cylinder irrespective of the position of said valve on said stud; and a washer carried on said stud forward of said valve provided with an aperture communicating with said annular passageway when said valve is seated on said head, and adapted to close the same when said valve is at the other end of its stroke away from said head; whereby fluid passes from the low pressure cylinder to the high pressure cylinder during initial operation of the piston element on its compression stroke, and is prevented from returning during completion of said stroke.

5. A fluid compressor comprising: a fluid reservoir; a low pressure cylinder supplied therefrom; a high pressure cylinder coaxial with said low pressure cylinder; a common piston element for said cylinders provided with a piston head working in the low pressure cylinder and a piston head working in the high pressure cylinder, there being a passageway in said latter head connecting said cylinders; a retaining stud extending from the forward end of said high pressure head; a floating valve loosely held on said stud for limited axial movement thereon and providing an axial annular passage around said stud communicating with said head passage when said valve is away from said head, said valve being adapted to close said head passage when seated against said head; and an axial bleed passage in said stud connecting said annular passage with the high pressure cylinder irrespective of the position of

said valve on said stud; whereby fluid passes from the low pressure cylinder to the high pressure cylinder during initial operation of the piston element on its compression stroke, and is prevented from returning during completion of said stroke.

6. A fluid compressor comprising: a fluid reservoir; a low pressure cylinder supplied therefrom; a high pressure cylinder coaxial with said low pressure cylinder; a common piston element for said cylinders provided with a piston head working in the low pressure cylinder and a piston head working in the high pressure cylinder, there being a plurality of longitudinal passageways in said latter head connecting said cylinders; a retaining stud extending from the forward end of said high pressure head; a floating valve loosely held on said stud for limited axial movement thereon and providing a passage communicating with said head passage when said valve is away from said head, said valve being provided with an annular insert fast to its rear face and adapted to close said head passages when seated against said head; and an axial bleed passage in said stud connecting said annular passage with the high pressure cylinder irrespective of the position of said valve on said stud; whereby fluid passes from the low pressure cylinder to the high pressure cylinder during initial operation of the piston element on its compression stroke, and is prevented from returning during completion of said stroke.

7. A fluid compressor comprising a fluid reservoir; a low pressure cylinder supplied therefrom; a high pressure cylinder coaxial with said low pressure cylinder; a common piston element for said cylinders provided with a piston head working in the low pressure cylinder and a piston head working in the high pressure cylinder, there being a passageway in said latter head connecting said cylinders; a retaining stud extending from the forward end of said high pressure head; a

floating valve loosely held on said stud for limited axial movement thereon and providing a passage communicating with said head passage when said valve is away from said head, said valve being adapted to close said head passage when seated against said head; and a washer carried on said stud forward of said valve provided with an aperture communicating with said valve passageway when said valve is seated on said head, and adapted to close the same when said valve is at the other end of its stroke away from said head; whereby fluid passes from the low pressure cylinder to the high pressure cylinder during initial operation of the piston element on its compression stroke, and is prevented from returning during completion of said stroke.

8. A fluid compressor comprising: a fluid reservoir; a low pressure cylinder supplied therefrom; a high pressure cylinder coaxial with said low pressure cylinder; a common piston element for said cylinders provided with a piston head working in the low pressure cylinder and a piston head working in the high pressure cylinder, there being a passageway in said latter head connecting said cylinders; a floating valve loosely held on the forward end of said high pressure piston head for limited axial movement with respect thereto and providing a passage communicating with said head passage when said valve is away from said head, said valve being adapted to close said head passage when seated against said head; and a washer forward of said valve provided with an aperture communicating with said valve passageway when said valve is seated on said head, and adapted to close the same when said valve is at the other end of its stroke away from said head, whereby fluid passes from the low pressure cylinder to the high pressure cylinder during initial operation of the piston element on its compression stroke, and is prevented from returning during completion of said stroke.

ALBERT E. ROY.
